US0D1100935S

(12) **United States Design Patent** (10) **Patent No.:** **US D1,100,935 S**
Hempel et al. (45) **Date of Patent:** **** Nov. 4, 2025**

(54) **DISPLAY SCREEN OR PORTION THEREOF WITH GRAPHICAL USER INTERFACE**

(71) Applicant: **FORUM US, INC.**, Houston, TX (US)

(72) Inventors: **Stefan Hempel**, Hamburg (DE);
Rumen Mittelstaedt, Hamburg (DE);
Leonard Maximilian Schroeter,
Hamburg (DE)

(73) Assignee: **FORUM US, INC.**, Houston, TX (US)

(**) Term: **15 Years**

(21) Appl. No.: **29/938,403**

(22) Filed: **Apr. 19, 2024**

CLAIM

The ornamental design for a display screen or portion thereof with graphical user interface as shown and described.

DESCRIPTION

The SOLE FIGURE is a front view of a display screen or portion thereof with graphical user interface showing our new design.

The outermost broken lines in the FIGURE show a display screen or portion thereof, and form no part of the claimed design. The remaining broken lines in the FIGURE show portions of the graphical user interface that form no part of the claimed design.

1 Claim, 1 Drawing Sheet
